US0D1083180S

(12) **United States Design Patent** (10) **Patent No.:** **US D1,083,180 S**
(45) **Date of Patent:** **** Jul. 8, 2025**

(54) **STAGE LIGHT FIXTURE PART OF**

29/507; F21V 15/00; F21V 15/01; F21V
15/02

(71) Applicant: **CLAY PAKY S.R.L.**, Seriate (IT)

See application file for complete search history.

(72) Inventors: **Alberto Alfier**, Seriate (IT); **Giovanni Zucchiniali**, Seriate (IT); **Carmine Pirozzi**, Seriate (IT); **Andrea Morra**, Seriate (IT)

(73) Assignee: **CLAY PAKY S.R.L.**, Seriate (IT)

(**) Term: **15 Years**

(21) Appl. No.: **35/520,655**

(22) Filed: **Apr. 21, 2023**

(80) **Hague Agreement Data**

Int. Filing Date: **Apr. 21, 2023**

Int. Reg. No.: **DM/228483**

Int. Reg. Date: **Apr. 21, 2023**

Int. Reg. Pub. Date: **Apr. 26, 2024**
